ATTACHMENT FOR WELL DRILLING RIGS

Filed May 14, 1927

Inventor
Ira H. Karns.

By George A. Purst

Attorney

UNITED STATES PATENT OFFICE

IRA A. KARNS, OF WICHITA FALLS, TEXAS, ASSIGNOR TO HERBERT J. HAUSLER

ATTACHMENT FOR WELL-DRILLING RIGS

Application filed May 14, 1927. Serial No. 191,350.

My invention consists in new and useful improvements in apparatus for use in raising and lowering the bailer, sand pump or swabbing device in well drilling, and is adapted to be used in connection with a rotary or standard drilling rig.

Heretofore, when it has been desired to bail or swab a well, it was necessary to unreel the drill line from the drum on which it runs, and reel on a swab or bailing line, an operation which not only causes a great loss of time, but involves considerable expense. A further disadvantage experienced in this procedure has been that after a line is once wound on the spool or drum, it has a tendency to become set, and when it is continuously unwound and rewound, it does not go back as it should, which results in a chafing and wear on the line.

It is the object of my invention to overcome these disadvantages and to this end I provide an auxiliary drum driven by the main source of power which operates the draw works of the derrick, and adapted to have the bailer or swab line reeled thereon, whereby it is unnecessary to alternately reel and unreel the drill line and said bailer or swab line on the main drum. It is obvious that with this arrangement, considerable time and money are saved in the drilling of a well.

With the above and other objects in view which will appear as the description proceeds, my invention consists in the novel features herein set forth, illustrated in the accompanying drawings and more particularly pointed out in the appended claims.

Referring to the drawings in which numerals of like character designate similar parts in both views,

Fig. 1 is a side elevation showing the device applied to a derrick, and

Fig. 2 is a view at right angle to Fig. 1.

In the drawings, 1 designates the floor of a rotary rig, having the usual jack posts 2 secured thereto, and extending upwardly

therefrom, connected together at their upper extremities by the head board 3. Rotatably mounted on the jack posts 2 in bearings 4, is the line shaft 5 having secured thereon a sprocket wheel for driving the conventional drum or hoist 6 supporting the drill line, all of which structure is in common use on rotary rigs.

In accordance with my invention, I secure an additional sprocket wheel 7 on the line shaft 5, adapted to be driven thereby, and operatively connected by means of a chain or belt 8 with an auxiliary drum 9 rotatably mounted on a shaft 9^a in bearings 10 at the lower end of a frame 11. This frame 11 consists of two or more upwardly extending supports 12 and 13, constructed of wood or iron or both, angularly disposed with respect to the jack posts 2, and secured at their lower extremities to a beam 14 through the medium of braces 15 which extend outwardly from an additional sill 16 on the derrick floor 1. The supports 12 and 13 are fastened at their upper ends to the head board 3 by bolts 17.

The auxiliary drum 9 is provided with a braking mechanism 18, operated by the lever 19, and on the shaft 9^a I provide a suitable clutch arrangement 20 controlled by the lever 21, for throwing the drum 9 into and out of operative engagement with the sprocket 7 and line shaft 5.

22 represents the bailer or swab line which is reeled on the auxiliary drum 9, and extends upwardly therefrom, over and under the idlers 23 and 24, respectively, which are rotatably mounted on shafts 25 and 26, secured on opposite sides of the supports 12 and 13. From the idler 24, the line 22 extends upwardly on the inside of the derrick to the top thereof, from whence it is brought over the sheave wheels or other pulleys (not shown) arranged for the purpose, and down on the inside of the derrick.

With my invention, it will be seen that when it is desired to bail or swab or go into

the hole for any purpose with tools or fishing devices, all that is necessary to do is to expend a few minutes time in attaching the bailer or swab or other tool and lowering them into the hole. When it is desired to re-continue drilling these may be withdrawn and the drilling machinery put into the hole immediately. Obviously, a great deal of time is saved and, as stated, the life of the drill lines 10 and the life of the swabbing or bailing lines is prolonged. The machine which, in itself comprises an auxiliary unit, is set back out of the way so as not to interfere with any of the present equipment used in connection with 15 a rotary rig, and its attachment involves no great amount of work, and its removal from place to place requires but little effort.

From the foregoing it is believed that my invention may be clearly understood without 20 further description, it being borne in mind that numerous changes may be made in the details of construction without departing from the spirit of the invention as set out in the appended claims.

25 What I claim and desire to secure by Letters Patent is:

1. The combination with a well drilling rig employing conventional draw works having a line shaft, of an auxiliary unit comprising 30 a drum for raising and lowering the swabbing or bailing devices in a well, said drum being rotatably mounted in an auxiliary frame, means for securing said frame to said rig just off the floor thereof and independent thereof, 35 and means whereby said drum is driven from the line shaft of the rig.

2. The combination with a well drilling rig employing conventional draw works having a line shaft, of an additional sprocket wheel 40 mounted on the line shaft, an auxiliary unit comprising a frame, means for securing said frame to the rig adjacent the line shaft and the hoist and just off the floor of said rig, an auxiliary drum rotatably mounted on said 45 frame and means whereby said drum is driven by said sprocket on the line shaft to raise and lower the bailing or swabbing devices.

3. An attachment for well drilling rigs employing conventional draw works having a 50 line shaft, consisting of an auxiliary unit, comprising a frame, means for securing said frame to the rig just off the floor thereof, a drum rotatably mounted in said frame, means for operatively connecting said drum with the line shaft, said drum being adapted to have a swabbing or bailing line reeled thereon, and a plurality of idler wheels mounted on said frame for engaging said line.

4. The combination with a well drilling rig 60 employing conventional draw works having jack posts and a line shaft, of a frame, means for securing said frame to the rig just off the floor thereof, and at an angle to the jack posts, bracing means for said frame, an auxiliary 65 drum rotatably mounted in said frame and

adapted to have a swabbing or bailing line reeled thereon, an additional sprocket wheel mounted on the line shaft and operatively connected with said drum whereby said drum is driven by said line shaft, a plurality of idler wheels on said frame for engaging said swabbing or bailing line, a clutch member, braking means in connection with said drum, and means for operating the same.

70 In testimony whereof I affix my signature. 75
